APPARATUS FOR PRODUCING AND EMPLACING CEMENTITIOUS SUBSTANCES

William E. Anderson and Francis C. Downey,
Kansas City, Mo., assignors to Jo Zach Miller, III, Kansas City, Mo., as trustee

Application July 24, 1939, Serial No. 286,240

8 Claims. (Cl. 91—44)

This invention relates to the art of coating surfaces with cementitious substances and the primary object is to provide a specially formed nozzle constituting a part of the apparatus by means of which a satisfactory layer of material may be emplaced.

Another important aim of this invention is the provision of the method of forming a cementitious substance immediately prior to emplacement, which method includes the novel steps of handling the materials and mixing the same so that an even flow of a plastic coating substance is obtained.

A further object of this invention is to provide a nozzle for apparatus for producing and emplacing cementitious substance, which nozzle is constructed to present a pair of intake ports that are formed and disposed to handle a supply of air and water, so that the former atomizes the latter, and so that the air will function as means for drawing sand and cement into the nozzle where such materials are rendered plastic and of proper consistency by the inclusion of water, which is intimately injected through the unique action of compressed air which enters the nozzle through the specially formed port.

Heretofore apparatus for applying cement coating to surfaces, has usually included means for driving the sand and cement toward an applying nozzle where the desired amount of liquid or water is injected so that a cementitious material is created. The sand and cement has also been fed into the material supply hose in ways which establish a pulsating action at the outlet end of the nozzle to the end that an uneven coating is presented, which must be smoothed, if the final covering is to be uniform in thickness. It is, therefore, one of the objects of this invention to provide a method and apparatus for producing and emplacing cementitious substances that will overcome the deficiencies found in machines now in commercial use, and likewise to present apparatus which will mix sand and cement without employing as much water as heretofore has been used so that the surface being coated is rendered water-

proof through the medium of a covering which is of higher density immediately adjacent to the surface being treated, and which is of progressively lower density as the outer face of the coating is approached.

This invention has for a further aim, the provision of a method of producing cementitious substances which includes the step of applying a primary coating of cement over the grains of sand by virtue of moisture thereon, and next by finally hydrating the mass of material to render plastic

the cement which has not been acted upon by the moisture on the sand at the time of the original mixing.

A large number of minor objects and advantages of the method and apparatus made in accordance with the present invention will become apparent to those skilled in the art as the details thereof are disclosed in the following specification, which refers to the accompanying drawing wherein:

Figure 1 is a schematic view of apparatus for 10 emplacing cementitious substances having a nozzle therein that is made in accordance with the present invention.

Fig. 2 is an enlarged fragmentary longitudinal central sectional view through the nozzle.

Fig. 3 is a vertical cross section through the nozzle, taken on line III—III of Fig. 2; and,

Fig. 4 is a similar view taken on line IV—IV of Fig. 2.

The nozzle illustrated in the drawing has been 20 found most satisfactory for applying a coating of plastic material in a manner that will be more fully hereinafter set down.

The nozzle per se comprises sections 6 and 8, the ends of which are in opposed, spaced apart relation and held in such position by coupling 10 which bridges the space between sections 6 and 8, and that is secured thereto through the medium of resilient gaskets 12, one of which circumscribes sections 6 and 8 respectively.

Rings 14 circumscribe sections 6 and 8 and have machine bolts 16 extending therethrough into the ends of coupling 10 so that as said machine bolts are tightened, the inner annular surfaces of gaskets 12 will be drawn into gripping engagement 35 with the respective sections. Thus, the nozzle is assembled and adjustment of the parts thereof made easy.

Sections 6 and 8 and coupling 10 are cylindrical, and the bore 18 through the body of the nozzle, 40 consists of the passages through sections 6 and 8. This bore 18 is substantially uniform in cross section and the inner surface thereof is smooth throughout its length.

Section 8 is relatively short and the free end 45 thereof establishes the end of the nozzle, which latter is usually maintained about 9 inches from the surface 20 being coated, as shown in Fig. 1. One end of section 6 may be, but is not necessarily in screw-threaded engagement with tubular joint 50 22, which in turn is attached to flexible hose 24 leading to hopper 26. The end of section 6 adjacent to the inner end of section 8 is reduced to substantially a feather-edge by tapering a portion of the length of said section to produce a frustro- 55

conical part, the outer surface 28 of which cooperates with the inner surface of coupling 10 in directing compressed air into bore 18.

Coupling 10 has an annular cavity 30 formed in the inner face thereof, which circumscribes the inclined face 28 of section 8. A similarly inclined annular surface 32 is formed on coupling 10 so as to present a continuous annular inclined passage 34, which when extended, will resolve into a point 10 on the longitudinal axis of bore 18. Another annular cavity 36 is formed in coupling 10, circumscribes the inner end of section 8 and annular shoulder 38 is perpendicular to the axis of section 8 and coupling 10 respectively. The end of section 8 is disposed close to shoulder 38 so that an intake port for liquid, such as water, is established in close proximity to the intake port for air, which is created by cavity 30 and passage 34.

A tube 40 places annular cavity 30 in communication with a source of compressed air, such as tank 42, and a valve 44 is provided to control the passage of air to the nozzle.

A tube 46 joins cavity 36 with a tank 48 which contains the water to be used in the nozzle, and a conventional valve 50 permits the operator to determine the amount of water which is introduced into the nozzle.

An intake port for air is therefore created from the tapered end of section 8, cavity 30 and passage 34. An intake port for water is created by the inner end of section 8, cavity 36 and shoulder 38. These intake ports are continuous and circumscribe the bore 18 in a fashion so as to cause the air to intersect the path of travel 35 of the water after the air and water are introduced into the nozzle through the intake ports just defined.

It is important that the air enter bore 18 close to the point of entrance of the water, for the 40 water is thereby atomized and mixed with incoming sand and cement immediately prior to its escape from the nozzle. The force of compressed air must be sufficient to draw the material, such as sand and cement, from hopper 26 and also 45 to atomize the water entering the intake port through cavity 36.

Air at 60 pounds pressure has been found preferable and when section 8 is approximately 6 inches long, the material passing therethrough 50 will assume a spiral path of travel through 2½ turns before reaching the free end of the section.

The inner face of section 8 near its outer end may be flared at a desired angle to decrease the velocity of the material and to cause the latter 55 to move radially from the axis of the nozzle at a greater angle as the surface being treated is approached.

An even flow of air through tube 40 insures an 60 associated even flow of material through the nozzle and the surface 20 is therefore evenly coated when the operator manipulates the nozzle through reciprocating paths of travel. It is ordinarily unnecessary to "trowel" or otherwise smooth the material after it has been applied to 65 the surface being coated. The layer of cementitious substance will adhere to surface 20 and be characterized by a denser lamination directly upon the surface. This character of coating is due to the rebounding of the sand grains from 70 surface 20 when the cementitious substance first reaches the surface being covered. The grains of sand strike surface 20 to produce a sand blasting effect and to leave directly thereon only the hydrated cement which was originally the coating 75 over the individual grains of sand and which

was a part of the mass passing through the nozzle. After the primary layer of relatively dense, substantially pure cement has adhered to surface 20, the sand will discontinue its separating action and the coating will become less dense by virtue of the grains of sand becoming progressively greater as the distance from the surface being treated is increased.

Systems now in use commonly employ from four to ten gallons of water to every ninety-four 10 pounds of cement. Through the application of water by the nozzle above described, two to two and one-half gallons of water per ninety-four pounds of cement is adequate. When the sand and cement is first mixed, every grain of sand 15 is coated with a certain amount of moisture and a fine coating of cement is collected thereon and carried to the nozzle and to the surface being treated without being dislodged. This primary coating of cement, which is on the grains of 20 sand, has collected a certain amount of moisture that was present on the sand and the amount of water introduced at the nozzle is only that required to sufficiently hydrate the mass so that the dry cement forming a part thereof is rendered 25 plastic to the desired degree.

The success of the present invention is due not only to the manner of mixing and conveying the material, but in the nozzle as illustrated and described, and since the concepts of the invention 30 permit embodying the same in structures having physical characteristics other than shown, it is desired to be limited only by the scope of the appended claims.

Having thus described the invention, what is 35 claimed as new and desired to be secured by Letters Patent is:

1. In apparatus for producing and emplacing cementitious substances, a tubular nozzle provided with a longitudinal bore for the passage 40 of material, an air intake port, and a liquid intake port, said air intake port being disposed to direct air across the path of travel of the liquid entering the nozzle through the said liquid intake port, said ports both being continuous and 45 circumscribing the bore of the nozzle.

2. In apparatus for producing and emplacing cementitious substances, a tubular nozzle provided with a longitudinal bore for the passage of material, an air intake port, and a liquid 50 intake port, said air intake port being disposed to direct air across the path of travel of the liquid entering the nozzle through the said liquid intake port, said ports both being continuous and circumscribing the bore of the nozzle, said air intake 55 being in close proximity to the liquid intake port whereby the liquid is atomized immediately prior to its combination with the material passing through the bore.

3. In apparatus for producing and emplacing 60 cementitious substances, a tubular nozzle provided with a longitudinal bore for the passage of material, an air intake port, and a liquid intake port, said air intake port being disposed to direct air across the path of travel of the liquid 65 entering the nozzle through the said liquid intake port, said ports both being continuous and circumscribing the bore of the nozzle, said air intake port being formed to direct a current of air toward a point on the longitudinal axis of the 70 bore and disposed in close proximity to the liquid intake port whereby the liquid is atomized immediately prior to its combination with the material passing through the bore.

4. In apparatus for producing and emplacing 75

cementitious substances, a tubular nozzle provided with a longitudinal bore for the passage of low water content cementitious material, a port for admitting compressed air into the bore, and

- 5 a port for admitting water into the bore, said ports having their discharge openings in the side of the bore and disposed in juxtaposition with the paths of travel of their discharge intersecting to cause the air to atomize the water as it enters
 10 the bore and prior to combination with the cementitious material passing therethrough; and means for controlling the supply of air and water respectively.

5. In apparatus for producing and emplacing cementitious substances, a nozzle having a cylindrical, smooth bore of substantially uniform cross section adapted to be connected with a source of supply of sand and cement, said nozzle being provided with an air intake port and a
 15 water intake port, said ports having their discharge openings in the side of the bore and disposed in juxtaposition with the paths of travel of their discharge intersecting whereby the water intersects the path of travel of the air at the side
 20 of the bore to atomize the former prior to its combination with the sand and cement passing through the bore, said nozzle constituting a sectional body; and a coupling having an inner surface formed to cooperate with the ends of the
 25 sections of said body to produce the aforesaid ports.

6. In apparatus for producing and emplacing cementitious substances, a nozzle having a cylindrical, smooth bore of substantially uniform cross
 30 section adapted to be connected with a source of supply of sand and cement, said nozzle being provided with an air intake port and a water intake port, said ports having their discharge openings in the side of the bore and disposed in
 35 juxtaposition with the paths of travel of their discharge intersecting whereby the water intersects the path of travel of the air at the side of the bore to atomize the former prior to its combination with the sand and cement passing
 40 through the bore, said nozzle constituting a pair of sections having ends in opposed spaced relation; and a coupling to clamp said sections in place, said coupling being provided with cavities
 45 through the bore, said nozzle constituting a pair of sections having ends in opposed spaced relation; and a coupling to clamp said sections in place, said coupling being provided with cavities

in the inner surface thereof to cooperate with the ends of said sections to produce continuous annular intake ports for the air and water respectively.

7. In apparatus for producing and emplacing 5 cementitious substances, a nozzle having a cylindrical, smooth bore of substantially uniform cross section adapted to be connected with a source of supply of sand and cement, said nozzle being provided with an air intake port and a water intake 10 port, said ports having their discharge openings in the side of the bore and disposed in juxtaposition with the paths of travel of their discharge intersecting whereby the water intersects the path of travel of the air at the side of the bore to atomize 15 the former prior to its combination with the sand and cement passing through the bore, said nozzle constituting a pair of cylindrical sections having ends in opposed spaced apart relation; and a cylindrical coupling in telescoped relation with 20 the sections, said coupling being provided with a pair of annular cavities in the inner face thereof, one of said cavities circumscribing the end of one section, the other cavity circumscribing the end of the other section. 25

8. In apparatus for producing and emplacing cementitious substances, a nozzle having a cylindrical, smooth bore of substantially uniform cross section adapted to be connected with a source of supply of sand and cement, said nozzle being provided with an air intake port and a water intake 30 port disposed in close proximity whereby the water intersects the path of travel of the air to atomize the former, said nozzle constituting a pair of cylindrical sections having ends in opposed spaced apart relation; and a cylindrical coupling in telescoped relation with the sections, said coupling being provided with a pair of annular cavities in the inner face thereof, one of said cavities circumscribing the end of one section, the other cavity circumscribing the end of the other section, the outer surface of one section near the end thereof being tapered to direct air entering the cavity circumscribing the said end toward a point on the longitudinal axis of the 40 bore of the nozzle. 45
